WELL REAMER

Dean Love, Fullerton, Calif., assignor to Chicksan
Oil Tool Company, Ltd., Fullerton, Calif., a cor-
poration of California

Application June 15, 1936, Serial No. 85,209

2 Claims. (Cl. 255—73)

This invention relates to a well drilling tool and relates more particularly to a well reamer. A general object of this invention is to provide a simple, practical and particularly efficient bore enlarging well reamer for use in the rotary method of well drilling.

Another object of this invention is to provide a well reamer operable to effectively and rapidly enlarge the rat-hole or reduced lower portion of a well bore.

Another object of this invention is to provide a bore enlarging well reamer embodying a plurality of rotatable disc cutters mounted to be particularly rapid and efficient in their cutting 15 action.

Another object of this invention is to provide a bore enlarging well reamer of the character mentioned in which the disc cutters do not become balled up or made inoperative by accumulations of mud and cuttings.

Another object of this invention is to provide a bore enlarging well reamer of the character mentioned in which the disc cutters are formed and mounted to have substantial clearance at 25 their trailing sides so that they are very rapid and efficient and do not become balled up with accumulations of mud and cuttings.

Another object of this invention is to provide a well reamer of the character mentioned embodying reaming disc cutters of novel and improved design.

Another object of this invention is to provide a well reamer of the character mentioned embodying simple, dependable means for rotatably 35 mounting the disc cutters.

A further object of this invention is to provide a well reamer of the character mentioned in which the disc cutters and the wear receiving bearings supporting the cutters may be easily 40 and quickly replaced.

The various objects and features of my invention will be fully understood from the following detailed description of a typical preferred form and application of the invention, throughout 45 which description reference is made to the accompanying drawing, in which:

Fig. 1 is a side elevation of the improved reamer provided by this invention. Fig. 2 is an enlarged transverse detailed sectional view taken substantially as indicated by line 2—2 on Fig. 1. 50 Fig. 3 is an enlarged fragmentary vertical detailed sectional view taken as indicated by line 3—3 on Fig. 2. Fig. 4 is a side or end elevation of one of the bearing sections for supporting a 55 disc cutter and Fig. 5 is a diametrical sectional

view of the bearing section taken as indicated by line 5—5 on Fig. 4.

The bore enlarging well reamer of the present invention includes, generally, a shank or body 10, a multiplicity of disc cutters 11 and means 12 5 rotatably mounting the cutters 11 on the body 10.

The body 10 of the reamer is adapted to be interposed or connected in a well drilling string. When the reamer is to be employed to enlarge a pilot bore or rat-hole the body 10 may be connected with the lower portion of the drilling string and may have a pilot bit connected with its lower end to guide the reamer in the rat-hole. The body 10 is an elongate member and may be 10 cylindrical in its general configuration. Suitable means are provided at the opposite ends of the body 10 to facilitate its connection in the drilling string. In the case illustrated in the drawing a tapered screw threaded pin 13 is provided on the upper end of the body 10 and a threaded 15 socket (not shown) may be provided in the lower end of the body. The body 10 may have a substantially intermediate portion 14 of enlarged diameter for carrying the cutters 11 and the cutter supporting parts. The body portion 14 20 may be cylindrical and the shoulders 15 at its opposite ends may be tapered or bevelled. A central longitudinal fluid passage 16 extends through the body 10 from one end to the other to 25 conduct the rotary mud or circulation fluid. 30

The body 10 is provided with means for receiving the cutters 11 and their mounting means 12. In the particular embodiment of the invention illustrated in the drawing there are two circumferential rows or series of cutters 11 and the portion 14 of the body 10 has two vertically spaced circumferential rows of projecting lugs or wings for carrying the cutters 11 and their mounting means 12. These wings are preferably 35 integral with the body portion 14 and are arranged in pairs, each pair comprising a forward wing 17 and a rear wing 18. The pairs of wings 17 and 18 in each set or series are equally circumferentially spaced and the corresponding pairs of wings 17 and 18 of the two sets or series 40 may be substantially vertically aligned as illustrated in Fig. 1. The wings 17 and 18 project laterally or outwardly from the body portion 14. The outer surfaces of the wings 17 and 18 are 45 suitably rounded and merge with the surface of the body portion 14. In accordance with the invention the wings 17 and 18 are pitched or inclined relative to the longitudinal axis of the body 10. The wings 17 and 18 are inclined or 50 pitched downwardly and forwardly relative to the 55

longitudinal axis of the body 10 and the direction of rotation of the reamer.

The wings 17 and 18 of each pair of wings are spaced apart to leave a recess 19 for carrying or receiving a cutter 11. The recesses 19 are preferably comparatively deep and extend into the body portion 14, as best illustrated in Fig. 2. The opposing inner sides or surfaces 20 and 21 respectively of the wings 17 and 18 are flat and parallel and are inclined downwardly and forwardly relative to the longitudinal axis of the body 10 and the direction of rotation of the reamer. The surfaces 20 and 21 comprise the side walls of the recesses 19. The invention 15 provides fluid ports 22 in the body 10 which extend outwardly from the passage 16 to the inner ends of the recesses 19. The ports 22 are adapted to discharge the circulation fluid outwardly against the cutters 11 in the recesses 19. The 20 pairs of wings 17 and 18 just described are preferably located adjacent the end shoulders 15 of the body portion 14.

The cutters 11 are in the nature of disc cutters and operate to shear the formation at the side 25 wall of the well bore when the reamer body 10 is rotated in the well. A disc cutter 11 is rotatably mounted in each recess 19 and where there are six pairs of wings 17 and 18, as just described, the reamer embodies six cutters 11. The cutters 30 11 may be identical in size and shape. The opposite sides of the cutters 11 may be flat and parallel. A central longitudinal opening 23 of substantial diameter is provided in each disc cutter 11. A counterbore or concentric socket 24 is provided in each cutter at the forward end of its opening 23. The cutters 11 are preferably of substantial diameter relative to the diameter of the body 10.

The disc cutters 11 are shaped to have particularly effective cutting cooperation with the earth formation and to remain free of accumulations of cuttings and mud. The peripheries of the cutters 11 are rather steeply pitched rearwardly and inwardly from the forward faces of the cutters leaving relatively sharp forward cutting edges 25. These cutting edges 25 are annular and unbroken. In accordance with the invention ridges or teeth 26 are provided on the peripheries of the cutters 11. The teeth are not necessarily sharpened. The teeth 26 provide ample metal stock for the active cutting edge portions of the cutters while the grooves or spaces occurring between the teeth 26 form clearance passages for the circulation fluid and the cuttings. The teeth 26 may be of rearwardly increasing depth whereby they do not come into active engagement with the formation at the side wall of the well bore. The action or operation of the cutters 11 will be hereinafter described.

60 The means 12 rotatably support the cutters 11 in the recesses 19 to project from the wings 17 and 18 so that they may act on the wall of the well bore. The assemblies or means 12 for rotatably supporting the several cutters 11 may be identical. Each cutter mounting means 12 includes a split or sectional bearing comprising, two like sections 27. The bearing sections 27 are cylindrical members and their inner opposing ends 28 are flat and normally in abutting cooperation. 65 The outer surfaces or ends 29 of the bearing sections 27 are flat and normal and are adapted to engage against the walls 20 and 21 of the recesses 19. Annular peripheral flanges 30 are provided on the bearing sections 27 at their outer ends. 70 The peripheral surfaces of the bearing sections 27

form the bearing surfaces for rotatably supporting the cutters 11. The bearing sections 27 are arranged within the cutters 11 to have their flanges 30 at the opposite ends or sides of the cutters. In the mounting means 12 for each cutter 11 the flange 30 of one bearing section 27 5 operates to space the rear side of the cutter from the wall or surface 21 while the flange 30 of the other bearing section is partially received in the socket 24 and projects therefrom to engage the wall or surface 20 and space the forward side of the cutter from the surface 20. Thus the bearing sections 27 are operable to transmit end thrusts from the cutters 11 directly to the wings 17 and 18 of the body. Longitudinal openings 31 15 are provided in the bearing sections 27. In the preferred construction the openings 31 are eccentric or offset from the central axis of the sections 27.

Pins 32 are provided to retain the bearing sections 27 in the recesses 19. The pins 32 are passed inwardly through openings 33 in the forward wings 17 and have their rear or inner portions threaded into openings 34 in the rear wings 18. The threads of the pins 32 and the openings 25 34 are preferably left-hand threads so that the pins have no tendency to unthread during operation of the reamer. The longitudinal axis of the openings 33 and 34 are inclined downwardly and rearwardly relative to the longitudinal axis of the body 10 and the direction of rotation of the reamer, being normal to the walls or surfaces 20 and 21. Sockets 35 are provided in the wings 17 at the forward ends of the openings 33. Heads 36 are provided on the forward ends of the pins 32 and are received in the recesses 35. The pins 32 having the heads 36 bearing in the sockets 35 and being threaded in the openings 34 operate to tie together the legs 17 and 18. The pins 32 pass through the openings 31 of the bearing sections 27 to retain the bearing sections and the cutters 11 in their proper positions in the recesses 19.

The invention provides means for relieving the pins 32 of practically all thrusts and pressures resulting from the active engagement of the cutters 11 with the wall of the well bore. A rib or key 38 is provided on the outer end 29 of each bearing section 27. The keys 38 are integral with the bearing sections 27. In practice the keys 38 are diametric of the openings 31 and are each divided into two parts by the presence of the openings 31. The keys 38 are rectangular in transverse cross section having flat sides and outer faces. Channels or grooves 39 are provided on the opposing inner surfaces of the wings 17 and 18 to receive the keys 38. The grooves 39 are rectangular in transverse cross section to rather accurately receive the keys 38 and are arranged to intersect the openings 33 and 34. In the preferred construction the grooves 39 extend substantially horizontally inward from the outer ends of the wings 17 and 18.

When assembling a cutter 11 and its bearing sections 27 in a recess 19 the assembly of the cutter and bearing sections is moved laterally or inwardly to enter the keys 38 in the outer end of the grooves 39. The assembly is then shifted inwardly until the openings 31 of the bearing sections 27 are properly aligned with the openings 33 and 34. The pin 32 is then inserted and threaded in place. The keys 38 cooperate with the grooves 39 to transmit the reaming or cutting thrusts directly to the body of the reamer and transmit the torque resulting from rotation of the cutters 11 directly to the body, thus relieving 70 75

the pins 32 of practically all pressures and strains resulting from the engagement of the cutters with the earth formation.

In operation the body 10 of the reamer may be connected in the lower portion of a well drilling string above a pilot bit. When the string is operated or rotated in the well bore the pilot bit operates in the pilot bore or rat-hole to guide the reamer. During rotation of the string the cutters 11 projecting outwardly from the legs 17 and 18 have their edges 25 in active engagement with the earth formation at the side wall of the well bore. The engagement of the cutters with the earth formation results in the independent rotation of the cutters about their individual axes. The relatively sharp forward peripheral edges 25 of the cutters 11 act to shear or cut away the earth formation as the reamer and the cutters 11 rotate. Owing to the substantial pitch of the peripheries of the cutters 11 there is a substantial clearance space C immediately behind each cutting edge 25 where it acts on the formation. Fig. 2 of the drawing illustrates the relationship of the cutters 11 to the wall of the well bore and shows the substantial clearance space C at the rear of each active cutting edge. These clearance spaces C allow the cutters 11 to clear themselves and provide for the circulation of the fluid and cuttings about the cutters. The teeth 26 and the spaces between the teeth provide turbulence or movement at the peripheries of the cutters and aid in keeping the cutters free of accumulations of mud and cuttings.

The circulation fluid discharging from the ports 22 impinges against the cutters 11 to flush them free of cuttings and to clear the teeth 26 of cuttings. The teeth 26 also strengthen the cutting edge portions of the cutters. The disc cutters 11 are of substantial diameter, and as they rotate during operation, present long active cutting edges 25. Because of their substantial length the cutting edges 25 are long wearing. The inclination or pitch of the cutters 11 increases their cutting efficiency and assures their proper individual rotation. The body 10 and its portion 14 are relatively small in diameter with respect to the effective diameter of the series of cutters 11 adapting the reamer for the enlarging of rat-holes. The six cutters 11 arranged in the two vertically spaced series effectively and fully ream or enlarge the bore.

The cutters 11 supported by the bearing sections 27 may freely rotate about their individual axes without wearing the body 10 and without imposing severe strains on the pins 32. The bearing sections 27 directly engage the walls or surfaces 20 and 21 for the transmission of end thrusts to the wings 17 and 18 while the keys 33 cooperate with the grooves 39 for the transmission of the torque stresses directly to the body wings. The bearing sections 27 thus relieve the pins 32 of practically all strains and relieve the pins and body of wear. The cutters 11 and their bearing sections 27 may be easily and quickly removed for replacement when worn.

Having described only a typical preferred form and application of my invention I do not wish to be limited or restricted to the specific details herein set forth, but wish to reserve to myself any variations or modifications that may appear to those skilled in the art or fall within the scope of the following claims:

Having described my invention, I claim:

1. A well reamer for use in a string of drilling tools including, a body to be interposed in said string, a disc cutter, and means mounting the disc cutter on the body to project outwardly therefrom at a point between its ends and to rotate about an axis inclined upwardly and forwardly relative to the longitudinal axis of the body and the direction of rotation of the reamer, the periphery of the cutter being inclined inwardly away from the leading peripheral edge of the cutter to leave clearance behind said edge, and teeth on the periphery of the cutter.

2. A well reamer for use in a string of drilling tools including, a body to be interposed in said string, circumferentially spaced pairs of spaced wings projecting outwardly from the periphery of the body in a plane between its opposite ends, a disc cutter between the wings of each of said pairs, the peripheries of the cutters being beveled away from the leading sides of the cutters to form cutting edges and to leave clearance at the peripheries of the cutters, teeth on the beveled peripheries of the cutters, and means rotatably supporting the cutters for rotation about downwardly and rearwardly inclined axes where they project outwardly from the wings.

DEAN LOVE. 50
